UNITED STATES PATENT OFFICE.

JOHN PENROD AND ROBERT D. THOMPSON, OF OKMULGEE, OKLAHOMA.

OIL-WELL PUMP.

Application filed May 4, 1923. Serial No. 636,681.

To all whom it may concern:

Be it known that we, JOHN PENROD and ROBERT D. THOMPSON, citizens of the United States, and residents of Okmulgee, in the 5 county of Okmulgee and State of Oklahoma, have invented certain new and useful Improvements in Oil-Well Pumps, of which the following is a specification.

This invention relates to pumping equipment for wells and one of the principal 10 objects is to provide for the increased capacity of the pumping equipment for a given size of tubing.

In the standard equipment it is necessary 15 to move the plunger and associated parts downwardly through the tubing and into the working barrel where the pumping operation takes place. Therefore, the diameter of the plunger is limited by the diameter of the tubing and thus the diameter of the tubing controls the pumping capacity 20 of the equipment.

In accordance with this invention the plunger is attached to the lower portion of 25 the tubing and does not move through the tubing so that the diameter of the plunger is not in any way regulated or limited by the diameter of the tubing.

A further object of the invention is to provide simple and practically automatic means 30 whereby the traveling valve upon being lowered through the tubing is clutched onto the plunger so that the same will reciprocate together as a unit, and, furthermore, the invention is provided with simple means 35 whereby the connection between the traveling valve and the plunger may be broken to permit of quick removal of the traveling valve and the standing valve carried thereby 40 without removing the plunger.

Another object of the invention is to provide a novel form of sand arrester or collector by means of which settling sand is 45 prevented from accumulating between the plunger and working barrel when the well is not in operation.

Other objects and advantages will be apparent during the course of the following description.

50 In the accompanying drawings forming a part of this application and in which like numerals are employed to designate like parts throughout the same,

55 Figure 1 is a vertical longitudinal sectional view through the pumping equipment,

the view illustrating the parts in the position they assume immediately after the introduction of the traveling and standing valves,

Figure 2 is a detail sectional view illustrating the plunger, the clutching-on collar and the supporting means for the plunger in the positions they occupy when the traveling and standing valves are withdrawn.

Figure 3 is a longitudinal sectional view 65 through the traveling and standing valves and the limited sliding connection between the traveling and standing valves.

Figures 4 and 4^a illustrate a longitudinal sectional view through the pumping equipment, the parts being in their pumping positions, and

Figures 5 and 5^a illustrate a slight modification of the invention.

In the drawings, wherein for the purpose 75 of illustration is shown a preferred embodiment of the invention, the numeral 5 designates a tubing which, as illustrated in Figure 2, has its lower portion provided with a coupling 6 to which a housing 7 is 80 connected. Figure 2 plainly illustrates that the housing 7 consists of a pair of sections joined by means of a bushing 8 which projects into the casing and constitutes a stop, the function of which will be fully described. 85

The lower portion of the housing 7 is provided with a bushing 10 into which a section 11 of a somewhat reduced diameter is threaded and the lower portion of the section 11 is in turn provided with a bushing 12 90 into which the seat 14 for the standing valve is threaded. Of course the usual perforated inlet nipple 15 is threaded on the lower portion of the organization for the admission of the liquid to be pumped up when the sucker 95 rod and the parts carried thereby are reciprocated.

The working barrel 16 is threaded through the bushing 8 and it will be seen that the working barrel is not movable 100 through the tubing but is suspended from the lower end of the same through the medium of the housing 7 and associated parts. The lower portion of the working barrel 16 has upper and lower packers 19 105 and 20, respectively, associated therewith, which packers have a tensioning spring 22 arranged between the opposed sides of the same. Figure 4^a illustrates that the spring 22 urges the packers firmly into engagement 110

with the working barrel 16 and the bushing 10. The space between the packers 19 and 20 is principally occupied by a suitable quantity of graphite to lubricate the plunger liner 25.

Figure 2 illustrates the manner of yieldingly suspending the plunger liner 25 within the working barrel so that the clutch member on the upper end of the same is in its inoperative or receptive position when the traveling and standing valves are withdrawn. More specifically, the upper portion of the plunger liner 25 is provided with a slotted connecting member 30 the upper portion of which is provided with a clutch collar slotted longitudinally to provide a plurality of arcuate gripping jaws 31. The longitudinal slots 33 in the clutch collar define a plurality of arcuate sections capable of being moved inwardly into gripping engagement with the traveling valve when the latter is introduced into the more or less permanent pumping mechanism of the well equipment.

Referring again to the yieldable supporting means for the plunger or liner 25 it will be seen that a spring 35 is confined between an annular member 36 and an inwardly projecting annulus or shoulder 37 on the inner side of what might be said to be a bumper sleeve 38. When the traveling valve has been withdrawn from the well, the bumper sleeve 38 rests upon the bushing 8 and the weight of the plunger and the clutching-on member which constitutes the arcuate sections 31 is transmitted through the spring 35 to the housing 7.

It is thus seen that the liner 25 and the clutch collar composed of the sections 31 are yieldingly supported and it is now pointed out that the clutch collar composed of the sections 31 is located within an outer clutch collar 40. The upper end of the clutch collar 40 is provided with a contact annulus 44 which extends into the tapered bore of the collar 40. Figure 2 illustrates that when the permanent parts of the equipment are in their respective positions the contact annulus 44 engages the upper end of the inner clutch collar so that the collar 40 is supported by the inner collar.

However, as the traveling valve is introduced into the well and into plunger liner 25, an annular shoulder 50 on the same contacts with an internal annular shoulder 51 on the connecting member 30 of the liner. Therefore, the weight of the traveling valve and the sucker rod, is now transmitted to the liner so that the tension of the coil spring 35 is overcome and the arcuate sections 31 are moved downwardly in the outer collar 40 and contracted firmly into engagement with the exteriorly tapered portion 54 of the traveling valve. When the arcuate sections 31 are thus engaged with the trav-

eling valve, the traveling valve and the liner move together as a unit during the reciprocation of the sucker rod 57.

In other words the liner and the upper and lower traveling valves cooperate in the formation of a plunger.

It is obvious that the traveling valve consists of upper and lower valves 58 and 59 respectively, which cooperate to prevent the return of the liquid and the same are of course provided with the usual seats held securely in place. Rings 60 surround the lower portion of the traveling valve and contact with the inner side of the liner to provide a liquid-tight connection between the liner and the traveling valve. By means of this, waste energy in pumping is reduced to a minimum.

Before proceeding to describe the standing valve and associated parts it is desired to describe the means for preventing sand from settling between the plunger and the working barrel when the well equipment is not in operation. The annular contact member 44 cooperates with the inwardly beveled upper ends of the sections 31 in forming an annular sand receiver by means of which the settling of sand between the plunger and the working barrel is prevented.

Each arcuate section 31, and more specifically, the beveled upper end of the same, is provided with a flap 65 which extends over the upper end of the adjacent slot 33 and thereby prevents sand from passing through the slot. Therefore, when the pumping apparatus is not in operation, the settling sand will collect on the sections 31 and the contact member 44 and when pumping is resumed the sediment will be taken up with the liquid.

The standing valve is indicated by the numeral 70 and has its lower end provided with an exteriorly tapered attaching portion 72 which is received within the nipple 14. The nipple 14 is of babbitt or other suitable material so that a secure connection will be provided between the same and the attaching portion 72. A ring 74 around the attaching portion 72 contacts with the tapered bore of the nipple 14 so as to prevent sand from lodging between the attaching portion 72 and the nipple. The lodging of sand between the attaching portion 72 and the nipple would possibly cause the attaching portion to stick when it is desired to withdraw the standing and traveling valves for replacement or other purposes. The bushing 12 is provided with an inwardly extending annular shoulder 76 with which the lower end of the attaching portion 72 flatly contacts.

Figure 3 illustrates that the standing valve is suspended from the traveling valve and the same are introduced into the well to

- gether. The connection between the standing and traveling valves consists of inner and outer slidably connected sections 80 and 81 respectively, the outer section being 5 provided with a closure or stop member 82 arranged in the path of travel of the head 84 of the section 80 so that the movement of the valves with relation to each other is limited.
- 10 However, it is important to note that the stroke of the traveling valve is less than the length of the tubular section 81 so that during the normal reciprocation of the traveling valve the standing valve will not be unseated.
- When the traveling and standing valves are introduced into the well, the tapered attaching portion 72 will be received within the nipple 14 and the head 84 will contact 20 with a spring 88 to firmly seat the attaching portion 72.
- Figure 4^a illustrates that the spring 88 is mounted upon a series of inwardly projecting lugs 90 located within the upper portion 25 of the standing valve 70.
- In use, the housing 7 is suspended from the tubing 5 and the working barrel 16 is, of course, mounted within the housing and is supported in the manner illustrated in 30 Figure 1, which figure illustrates that the packing members 19 and 20 cooperate with and form what might be said to be a portion of the working barrel.
- As illustrated in Figure 2, the lower end 35 of the outer collar 40 is spaced above the bumper sleeve 38 and when the traveling valve is introduced, the outer collar 40 will contact with the bumper sleeve 38 and be stopped thereby. The inner collar will continue to move downwardly until the same 40 is firmly gripped with the traveling valve. Of course, this is brought about by the engagement of the shoulder 50 with the shoulder 51 and the consequent transmission of 45 the weight of the traveling valve and sucker rod through the liner 25 and the spring 35.
- The tapered attaching portion 72 is snugly received in the nipple 14 and as previously stated, the ring 74 provides a means 50 to exclude sand from between the attaching portion and the nipple and also serves to prevent the return of the fluid.
- As the traveling valve continues to move 55 downwardly, subsequent to the seating of the standing valve, the section 80 will move into the tubular section 81 and when the head 84 is engaged with the spring 88, the attaching portion 72 is more firmly seated.
- As the arcuate sections 31 are now 60 securely clutched onto the traveling valve 54, the reciprocation of the sucker rod will cause the liner 25 to operate with the traveling valve and cooperate with the same in the formation of a plunger.
- 65 As brought out in the objects of the in-
- vention, a pump constructed in accordance with this invention, has a large capacity in proportion to the diameter of the tubing 5. This is accounted for by the fact that the liner 25 does not have to pass through the tubing but is suspended from the lower end of the same. In fact, it will be seen that the diameter of the plunger is greater than the diameter of the tubing and consequently the displacement is substantially increased. 75
- When it is desired to remove the traveling valve and the standing valve, it is merely necessary to move the sucker rod upwardly beyond the normal stroke so that the annulus 44 will contact with the bushing 6 and this action will cause the arcuate sections to separate somewhat and thereby permit of the continued upward movement of the traveling valve and of the unseating of the standing valve. When the parts have been 80 removed, the arcuate sections 31 are in position to again receive the detachable portions of the mechanism when returned to the well.
- It might be added that when the traveling valve is not in the well the parts occupy the position illustrated in Figure 2 wherein it is shown that the spring 35 supports the liner and maintains the lower end of the outer clutch member 40 in spaced relation 85 to the upper end of the bumper sleeve. When the traveling valve is introduced into the liner the shoulder 50 will contact with the shoulder 51 and move the liner downwardly against the pressure of the coiled spring 35. At this time the outer clutch section 40 will engage the bumper sleeve 38 and further downward movement of the outer clutch member 40 is prevented. However the inner clutch sections 31 continue to 90 move downwardly and are drawn together or are compressed into gripping engagement with the tapered portion of the traveling valve, this feature being clearly illustrated in Figure 1.
- When it is desired to detach the traveling valve and withdraw the same, it is merely necessary to pull upwardly on the traveling valve so that the contact member 44 will engage the coupling 6 and the clutch sections 31 will continue to move upwardly until they occupy the position illustrated in Figure 2. This therefore releases the clutch sections 31 from engagement with the traveling valve so that the traveling valve will be 100 permitted to be withdrawn.
- Attention is directed to the fact that as the traveling valve is withdrawn from the well the clutch sections and the liner automatically resume their respective positions so that when the traveling valve is again introduced into the well, it may be clutched onto the liner without the necessity of first arranging the parts to receive the traveling valve. 105
- 110
- 115
- 120
- 125
- 130

In the modified form of the invention illustrated in Figures 5 and 5^a, the sucker rod 100 supports a single traveling valve 101, the lower portion of which is exteriorly tapered for engagement by a plurality of arcuate sections 102 which cooperate with a clutch collar 103. That is to say, the arcuate sections 102 are exteriorly tapered and the bore of the clutch collar 103 is oppositely tapered so that the weight of the sucker rod and the working barrel 104 will pull the arcuate sections downwardly and inwardly firmly into gripping engagement with the cage of the single traveling valve. Figure 15 5^a illustrates that the lower portion of the working barrel 104 is mounted upon a spring 106 sufficiently strong to support the weight of the plunger when the single traveling valve is removed. However, when the single 20 traveling valve and the sucker rod are introduced into the well, the weight of the sucker rod and traveling valve is transmitted through the plunger and the spring 106 so that the arcuate sections 102, connected 25 to the plunger, are forcibly moved downwardly.

In this form of the invention, the standing valve 107 is permanently secured to a lower bushing 108 and is not removable with the 30 single traveling valve. Also the lower traveling valve 110 is fixed within the upper portion of the plunger 104 and is separate and apart from the upper traveling valve so that it remains within the well when the 35 upper traveling valve is removed.

When it is desired to repair the upper traveling valve 101, it is merely necessary to pull upwardly beyond the normal stroke of the sucker rod and the arcuate sections 102 will be released from gripping engagement with the tapered portion of the traveling valve. This is brought about by the engagement of the head 112 with a bushing 114 between the housing 115 and the tubing 116. 45 When the traveling valve has been removed the parts are again in position to receive the traveling valve after the necessary repairs or replacements have been made.

In summarizing, it will be seen that the 50 invention is provided with a liner which is not in any way restricted as to diameter with relation to the diameter of the tubing. This is true because the liner is permanently suspended below the tubing and is not passed 55 through the tubing with the traveling and standing valves.

By permanently suspending the liner 25 below the tubing the external diameter of the traveling valve may be almost as great 60 as the internal diameter of the tubing and this allows large valves and large valve cages to be employed. The substantial increase in the size of the ball valves and the cages therefor brings about a substantial increase 65 in production and it will be seen that the

various passages and by-passes for the oil are very generous.

Attention is directed to the fact that the various parts of the mechanism are not merely enlarged to bring about a corresponding increase in production as the tubing which is one of the most expensive elements in the organization remains of a small diameter while the production is substantially increased.

It will be seen that the cost of placing the oil in the tank will be greatly lessened as it is not necessary to increase the tubing diameter to bring about a substantial increase in production.

With reference to Figure 4, it will be seen that the shoulder 50 and the shoulder 51 flatly contact with each other so as to form a seal which prevents the return of the oil. In this manner they cooperate with the rings 60 which bear against the inner wall of the bushing 52.

We claim:

1. In a pumping mechanism, a tubing, a liner yieldingly supported beneath the tubing, and a traveling valve movable into the liner, there being means to grip the traveling valve to the liner whereby the traveling valve cooperates with the liner in the formation of a plunger.

2. In a pumping mechanism, a tubing, a liner permanently and yieldingly suspended beneath the tubing, and a traveling valve movable through the tubing and into the liner, there being means to detachably connect the traveling valve to the liner whereby the traveling valve cooperates with the liner in the formation of a plunger, the traveling valve being removable through the tubing independently of the liner.

3. An oil well pump comprising a tubing, a liner permanently and yieldingly suspended below the tubing and being of a greater diameter than the diameter of the tubing, a traveling valve movable through the tubing and into the liner, and a clutching-on mechanism adapted for connecting the liner to the traveling valve whereby the traveling valve cooperates with the liner in the formation of a plunger.

4. A pumping mechanism for wells comprising a tubing, a fixed working barrel suspended below the tubing, a liner yieldingly mounted within the working barrel and being permanently located beneath the tubing, and a traveling valve movable through the tubing, there being means to detachably connect the traveling valve to the liner whereby the liner and the traveling valve cooperate in the formation of a plunger.

5. A pumping mechanism for wells comprising a tubing, a fixed working barrel suspended below the tubing, a liner yieldingly within the working barrel and being permanently located beneath the tubing,

- traveling valve movable through the tubing, there being means to detachably connect the traveling valve to the liner whereby the liner and the traveling valve cooperate in the formation of a plunger, and a housing suspended from the tubing and receiving the working barrel and the plunger.

6. In a large capacity pump, the combination of a tubing, a liner permanently and yieldably supported below the tubing, a traveling valve movable through the tubing and adapted to be received within the liner, a clutching mechanism for connecting the traveling valve to the liner and consisting of an inner compressible traveling valve engaging section and an outer compressing section, and a standing valve suspended from the traveling valve.

7. In a large capacity pump, the combination of a tubing, a liner permanently and yieldably supported below the tubing, a traveling valve movable through the tubing and adapted to be received within the liner, a clutching mechanism for connecting the traveling valve to the liner whereby the two reciprocate together and cooperate in the formation of a plunger, and a standing valve suspended from the traveling valve, the liner diameter being independent of the internal diameter of the tubing whereby the liner has a large displacement in comparison to the internal diameter of the tubing, said clutching mechanism consisting of an inner traveling valve gripping member and an outer member for compressing the inner member.

8. A pumping mechanism for wells comprising a tubing, a housing suspended from the tubing and having a stop member; a liner arranged within the housing, a bumper sleeve surrounding the liner and having a shoulder, a spring mounted on the shoulder and yieldably supporting the liner, co-acting clutch members mounted on the upper portion of the liner, and a traveling valve movable through the tubing and adapted to be received within the liner, said clutch members being adapted to secure the traveling valve to the liner whereby the traveling valve and the liner reciprocate together and cooperate in the formation of a plunger.

9. A pumping mechanism for wells comprising a tubing, a housing suspended from the tubing and having a stop member, a liner arranged within the housing, a bumper sleeve surrounding the liner and having a shoulder, a spring mounted on the shoulder and yieldably supporting the liner, co-acting clutch members mounted on the upper portion of the liner, a traveling valve movable through the tubing and adapted to be received within the liner, said clutch members being adapted to secure the traveling valve to the liner whereby the traveling valve and the liner reciprocate together and

cooperate in the formation of a plunger, and a standing valve suspended from the traveling valve.

10. A pumping mechanism for wells comprising a tubing, a housing suspended from the tubing, a liner arranged within the housing, a bumper sleeve surrounding the liner and having a shoulder, a spring mounted on the shoulder and yieldably supporting the liner, co-acting clutch members mounted on the liner, a traveling valve movable through the tubing and adapted to be received within the liner, said clutch members being adapted to secure the traveling valve to the liner whereby the traveling valve and the liner reciprocate together and cooperate in the formation of a plunger, a standing valve suspended from the traveling valve, and a packing arranged beneath the working barrel and within the housing.

11. A pumping mechanism for wells comprising a housing having a stop member, a working barrel secured within the housing, a bumper sleeve surrounding the working barrel, a liner received within the working barrel and yieldably supported by the bumper sleeve, coacting clutch members secured to the liner and consisting of inner and outer bodies, the opposed sides of which are correspondingly tapered, and a traveling valve having a tapered portion adapted to be gripped by the inner clutch member.

12. In a fluid pumping mechanism, the combination of coacting clutch members, one of which consists of a series of arcuate gripping jaws having their opposed edges in spaced relation, and flaps extending over the space between the opposed edges of the jaws to exclude sand in the fluid.

13. In a fluid pumping mechanism for wells, the combination of a clutch member consisting of a plurality of arcuate sections having their opposed edges arranged in spaced relation, and means extending over the space between the said sections to exclude sand in the fluid, and means whereby to draw said sections inwardly.

14. In a pumping mechanism for wells, the combination with a tubing, of a bushing connected to the tubing, a housing connected to the bushing, a working barrel fixed within the housing, a liner movable in the working barrel and having its upper portions formed with inner and outer clutch members, the inner member consisting of a plurality of arcuate sections, and a traveling valve having a tapered portion adapted to be gripped by said arcuate sections.

15. In a pumping mechanism for wells, the combination with a tubing, of a bushing connected to the tubing, a housing connected to the bushing, a working barrel fixed within the housing, a liner movable in the working barrel and having its upper portions formed with inner and outer clutch

members, the inner member consisting of a plurality of sections, a traveling valve having a tapered portion adapted to be gripped by said sections, the opposed sides of said inner and outer clutch members being correspondingly tapered.

16. In a pumping mechanism for wells, the combination of a tubing, a bushing suspended from the same, a housing connected to the bushing, a working barrel fixed within the housing and provided with packers at the lower ends thereof, a liner received within the working barrel and having its upper portion formed with co-acting clutch members, one of which is adapted to be engaged by said bushing to separate the sections from locking engagement with each other, a bumper sleeve arranged within the housing and yieldably supporting the liner, said housing being provided with a stop member upon which said bumper sleeve rests, and a nipple secured in the lower portion of the housing and adapted for the reception of the attaching portion of a standing valve.

17. A pumping mechanism for wells comprising a housing, a working barrel secured within the housing, a plurality of packers secured at the lower portion of the working barrel, a liner received in the working barrel and extending beyond the ends thereof, a traveling valve movable into said liner, said traveling valve and said liner being provided with coacting shoulders by means of which the liner is lowered when the traveling valve enters the liner, and a clutching mechanism for connecting the traveling valve to the liner.

18. A pumping mechanism for wells comprising a housing, a working barrel secured within the housing, a plurality of packers secured at the lower portion of the working barrel, a liner received in the working barrel, a traveling valve movable in said liner, said traveling valve and said liner being provided with coacting shoulders by means of which the liner is lowered when the traveling valve enters the liner, a clutching mechanism for connecting the traveling valve to said liner, and a standing valve having a limited sliding connection with said traveling valve and suspended therefrom.

19. In a pumping mechanism, the combination of a housing having a nipple, a traveling valve received within the housing, a standing valve suspended below the traveling valve and having a limited sliding connection, the limited sliding connection consisting of telescoping members having their ends provided with contact members, and a spring received within the outer member and arranged in the path of travel of one of the contact members whereby the contact member compresses the spring and urges the

traveling valve into said nipple on the downward movement of the traveling valve.

20. A pumping mechanism comprising a traveling valve, a liner, a body mounted on the liner and having slots defining a plurality of gripping members, and a clutch collar receiving the body and having means to urge the body into gripping engagement with a traveling valve.

21. A pumping mechanism comprising a liner, a body mounted on the liner and having a plurality of gripping members, a clutch collar receiving the body and having means to urge the body into gripping engagement with a traveling valve whereby the valve and the liner are reciprocated together, said clutch collar being provided with a contact member in the path of travel of said body whereby the engagement of the body with the contact member releases said gripping members from engagement with the traveling valve.

22. A pumping mechanism comprising a body having a series of arcuate gripping members, a clutch collar surrounding the gripping members, the opposed sides of the gripping members and the collar being oppositely tapered whereby the downward movement of the gripping members in the collar urges the gripping members inwardly.

23. A pumping mechanism comprising a body having a series of gripping members, a clutch collar surrounding the gripping members, the opposed sides of the gripping members and the collar being oppositely tapered whereby the downward movement of the gripping members in the collar urges the gripping members into engagement with a traveling valve, and a striking element arranged in the path of travel of said collar and adapted to release the collar from gripping engagement with the body whereby the body is released from engagement with the traveling valve to permit of the free removal of the traveling valve.

24. A pumping mechanism comprising a tubing, a liner suspended from the tubing and having a body provided with gripping members, a clutch collar receiving the gripping members, a traveling valve movable through the body, the opposed sides of said traveling valve and said body being oppositely tapered, said collar being adapted to urge said gripping members firmly into engagement with the tapered portion of the traveling valve, there being means in the path of travel of said collar to release the collar from gripping engagement with the body whereby the traveling valve may be removed from the liner and withdrawn through the tubing independently of the liner.

25. A pumping mechanism comprising a tubing, a bushing carried by the tubing, a housing connected to the bushing, a liner

- yieldingly supported within the housing and having a clutch body, a clutch collar receiving said body, a traveling valve movable through the body, said collar being adapted 5 to move the body inwardly into gripping engagement with the traveling valve whereby to rigidly connect the traveling valve to the liner, said collar being adapted to engage said bushing when the traveling valve 10 is moved upwardly beyond a predetermined distance to release the body from gripping engagement with the traveling valve whereby the traveling valve is separated from the liner and withdrawn through the tubing independently of the liner.
26. A pumping mechanism comprising a liner having a connecting bushing provided with a shoulder, and a traveling valve movable through the connecting bushing and 20 having a shoulder adapted to flatly contact with the first named shoulder whereby the clutch of the traveling valve is borne by the liner and whereby the two shoulders form a liquid seal.
27. A pumping mechanism comprising a liner having a connecting bushing provided with a shoulder, and a traveling valve movable through the connecting bushing and having a shoulder adapted to flatly contact 25 with the first named shoulder whereby the clutch of the traveling valve is borne by the liner and whereby the two shoulders form a liquid seal, and packers confined between the traveling valve and the bushing and cooperating with said shoulders in providing a liquid seal.
28. A pump comprising a housing having a stop, a working barrel in the housing, a liner received in the working barrel, a clutch 40 carried by the liner, a liner carried contact member for operating said clutch, said stop being in the path of travel of said contact member and adapted for operating the same, and means normally spacing said contact member from said clutch.
29. A pump comprising a housing having a stop, a working barrel in the housing, a liner received in the working barrel, a clutch carried by the liner, a liner carried contact 45 member for operating said clutch, said stop
- being in the path of travel of said contact member and adapted for operating the same, and means normally spacing said contact member from said clutch, said clutch consisting of inner gripping sections and an outer section to move the inner sections to operative position.
30. A pump comprising a traveling valve, a housing having a stop, a working barrel in the housing, a liner received in the working barrel, a clutch carried by the liner, a liner carried contact member for operating said clutch, said stop being in the path of travel of said contact member and adapted for operating the same, means normally spacing 60 said contact member from said clutch, said clutch consisting of inner gripping sections and an outer section to move the inner sections to operative position, said traveling valve and said liner being provided with co-acting shoulders by means of which the weight of the traveling valve is transmitted to the liner.
31. A pumping mechanism including a removable valve and comprising a liner, a sleeve surrounding the liner, a spring supported by said sleeve, and yieldingly supporting said liner, and means carried by said liner for gripping engagement with the removable valve.
32. A pumping mechanism including a removable valve and comprising a liner, a sleeve surrounding the liner, a spring supported by said sleeve, and yieldingly supporting said liner, and means carried by said liner for gripping engagement with the removable valve, said means being operated by said sleeve.
33. A pumping mechanism for wells comprising a traveling valve, a liner having its upper portion provided with a traveling valve engaging clutch, means yieldingly supporting the liner, a housing receiving said liner and said means and having a coupling in the path of travel of and adapted to be engaged by said clutch, and a working barrel carried by said housing and receiving said liner.

JOHN PENROD.
ROBERT D. THOMPSON.
